STOP MOTION FOR SPINNING AND LIKE
TEXTILE FRAMES

Gordon Scott Fraser, Arbroath, Scotland, assignor to Douglas Fraser & Sons Limited, Arbroath, Angus, Scotland, a corporation of Great Britain

Application October 16, 1945, Serial No. 622,675
In Great Britain March 5, 1945

2 Claims. (Cl. 57—84)

1

This invention relates to an improved stop motion mechanism for spinning and like textile frames of that class incorporating a detector or feeler which is held in inoperative position by the fibrous material during the normal operation of the frame, and feed-stopping mechanism which is rendered operative on movement of the detector or feeler on the occurrence of breakage or failure of the material.

Mechanism according to one embodiment of the invention includes a detector or feeler depending from a block in bearing engagement with a fixed pivot or a knife-edge, to a point of which block spaced from said fixed pivot or knife-edge is pivotally connected one end of a link pivotally connected at its opposite end to the forward arm of a manually operable lever. The several pivots are substantially aligned in the position occupied by the detector or feeler when the detector or feeler is in engagement with the material, the block and the link constituting in effect a toggle device.

The manually operable lever is mounted between its ends on a fixed pivot, and the remote arm of said lever is pivotally connected to a weighted lever formed adjacent to its pivot with a nose engageable with a pivotally supported arm carrying the arbor of the retaining pressing roller.

The pivot of said arm may be the pivot of the manually operable lever.

In setting the mechanism the free or forward end of the manually operable lever is depressed, and the toggle brought to approximately dead centre position; the weighted lever is in raised position, and held there as the manually operable lever is latched by the toggle device, while the nose projecting from the weighted lever abuts on the arbor-carrying arm whereby the retaining pressing roller is held against its companion retaining roller.

An extension of the weighted lever presents a nipping element co-operative with a stationary nipping element so arranged that on operation of the stop motion the material is held at a point beneath the retaining rollers before the retaining rollers are separated.

If, now, on breakage of the material, the detector or feeler swings outwardly, the toggle is broken, the forward arm of the manually operable lever is tilted upwardly as the weighted lever falls, the material is gripped between the nipping elements and held against further feed-in, the arbor-carrying arm is free to tilt and the retaining pressing roller moves under the action of its own weight and that of the arbor-carrying arm

2

in the direction away from its companion retaining roller.

To reduce friction between the link and the block, the lower end of the link, in lieu of carrying a pivot pin, may be formed with a projecting knife-edge element (the edge of which may be rounded) engaging a suitably shaped socket opening in the block.

In a modification the arbors of the retaining pressing roller and of the drawing pressing roller are carried by arms of a multi-armed lever the fulcrum pin of which is movable in a slot, said multi-armed lever being influenced by a spring to withdraw the rollers carried thereby from their companion rollers when the weighted lever falls.

In the accompanying drawings Fig. 1 is an end elevation partly in section of a stop-motion according to the invention. Fig. 2 is a detail view of a modified mounting of the link; Fig. 3 is a view similar to Fig. 1 but showing a modification in which the retaining pressing roller and the drawing pressing roller are adapted to be moved simultaneously away from their companion rollers.

The mechanism illustrated in Fig. 1 includes a detector or feeler 1 depending from a block 2 formed with a bearing face for engagement by a fixed knife-edge member 3, to a point 4 of which block 2 spaced from the knife-edge is pivotally connected one end of a link 5 pivotally connected at its opposite end at 6 to the forward arm 7 of a manually operable lever. The pivots 4 and 6 are substantially aligned with the knife-edge in the position occupied by the detector or feeler 1 when the detector or feeler is in engagement with the material indicated at A, the block 2 and the link 5 constituting in effect a toggle device.

The manually operable lever is mounted between its ends on a fixed pivot 8, and the remote arm 9 of said lever is pivotally connected to a weighted lever 10 formed adjacent to the pivot 8 with a nose 11, engageable with an arm 12 pivoted at 8 and carrying the arbor 13 of the retaining pressing roller 14.

In setting the mechanism the free or forward end of the manually operable lever is depressed, whereby the toggle is allowed to assume approximately dead center position in which it is retained by the action of the material on the feeler 1; the weighted lever 10 is in raised position, and held there as the manually operable lever 7, 9 is latched by the toggle device, while the nose 11 projecting from the weighted lever 10 abuts on the arbor-carrying arm 12 whereby the retaining pressing roller 14 is held against its companion retaining roller 15.

3

If, now, on breakage of the material, the detector or feeler 1 swings outwardly under the action of gravity, the block 2 is rocked so that the knife-edge is no longer in line with the points 4 and 6, and the forward arm 7 of the manually operable lever is tilted upwardly about the pivot 8 by the action of the weighted lever 10 on the arm 9. The weighted lever 10 swings about its pivotal connection with the lever arm 9, while the extension 16 of said lever 10 swings upwardly and grips the material between the nipping element 17 and the stationary nipping element 18 at a point beneath the retaining roller. With further downward movement of the weighted lever 10 in an arc about the pivotal connection with the lever arm 9, the nose 11 no longer presses against the arm 12, so that the retaining pressing roller 14 is free to move under the action of its own weight and that of the unbalanced arm 12 in the direction away from its companion retaining roller 15.

In the modification shown in Fig. 2 the link 5 presents at its lower end a knife-edge member 5a engaging the inverted V-shaped upper portion of a recess 2a formed in the block 2.

In the modification illustrated in Fig. 3 the retaining pressing roller and the drawing pressing roller are jointly movable towards and from their companion rollers, and in this figure parts corresponding to those in Fig. 1 are indicated by the same reference numerals distinguished by the addition of the exponent '.

In this construction the link 5' is connected to an extending arm of a lever 21 crooked at the end remote from the link connection 6' and pivoted on a stationary pin 22. The lever 21 carries a pin 23 on which is pivoted a manually operable multi-armed lever 24, the forwardly extending arm of which forms a handle 25, while the rearwardly extending arm is furnished with a weight 26. A downwardly extending arm 21' of the lever 24 is furnished with a pin 28 on which is fulcrumed a further multi-armed lever 29, the pin 28 engaging in a slot 30 in a forked arm 31 of the lever 29. The lever 29 carries at its opposite ends the arbor 13' of the retaining pressing roller 14' and the arbor 32 of the drawing pressing roller 19', respectively.

A tension spring 33 is connected at one end to the lever 29 and at the opposite end to a stationary part of the frame.

The retaining pressing roller 14' and the drawing pressing roller 19' are normally held pressed against their respective companion rollers 15' and 20' with the material interposed in the nips of said rollers, by pressure of the pin 28 against the end wall of the slot 30 under the influence of the weighted lever 24.

When, now, on breakage or failure of the material, the detector or feeler 1' swings outwardly, the toggle is broken, the block 2' leaves the knife-

edge member 3' and the lever 24 is tilted and tilts the lever 21 about the pivot 22. At the same time the weighted lever 24 is retracted in the direction of the arrow B by means of a projecting finger 34 on the lever 24 coming into contact with and sliding down an inclined surface presented by a slide member 35 extending angularly from the stationary frame. This retractive movement of the lever 24 draws the pressure pin 28 backwards in the slot 30, whereby the pressure of the retaining rollers 14', 19' is released, the movement of the pin 28 providing a clearance in the slot 30 which permits the spring 33 to withdraw the lever 29 and move the rollers 14' and 19' away from their respective companion rollers 15', 20'.

The backward movement of the lever 29 is limited by a fixed stop 36 and by an extension arm 37 of the lever 21.

The mechanism is reset by means of the handle 25 operating the weighted lever 24.

What is claimed is:

1. A stop motion mechanism for spinning and like textile frames having a retaining pressing roller, and a companion roller, comprising a member affording a pivot bearing and a feeler forming with said member a unit, a stationary knife-edged member engageable with the bearing, a link having at one end a permanent pivotal connection with said first mentioned member, a lever to which said link is pivoted at its other end, said link and said first mentioned member constituting limbs of a toggle, and a weight device influencing said lever, said weight-device normally functioning to urge the retaining pressing roller against its companion roller, but being free to fall on the breaking of the toggle.

2. Stop motion mechanism as claimed in claim 1 for spinning and like textile frames having a retaining pressing roller and a drawing pressing roller and companion rollers cooperative with said pressing rollers to draw out the yarn, said mechanism including a multi-armed lever pivoted to the weight-influenced lever, and carrying said retaining pressing roller and said drawing pressing roller.
